UNITED STATES PATENT OFFICE.

ISAAC C. TERRY, OF BUENA VISTA, COLORADO.

LAMP-SHADE.

1,149,004.

Specification of Letters Patent.

Patented Aug. 3, 1915.

Application filed November 28, 1914. Serial No. 874,456.

To all whom it may concern:

Be it known that I, ISAAC C. TERRY, a citizen of the United States of America, residing at Buena Vista, in the county of Chaffee and State of Colorado, have invented new and useful Improvements in Lamp-Shades, of which the following is a specification.

This invention relates to improvements in lamp shades and has particular application to an adjustable shade.

In carrying out the present invention, it is my purpose to provide a lamp shade of the canopy type wherein the canopy or shade may be swung toward and away from the lamp so that the area illuminated by the light rays issuing from the lamp may be decreased and increased according to the movement of the canopy.

It is also my purpose to provide a device of the class described wherein the canopy may be adjusted with ease and convenience and held in adjusted position for the desired period of time.

A further object of my invention is to provide an adjustable lamp shade or canopy which will embrace the desired features of simplicity, efficiency and durability, which may be manufactured and marketed at a minimum expense and which may be applied to lamps illuminated by electricity, gas, oil, etc.

With the above and other objects in view, the invention consists in the construction, combination and arrangement of parts hereinafter set forth in and falling within the scope of the claim.

In the accompanying drawing; Figure 1 is a top plan view of a lamp shade constructed in accordance with the present invention. Fig. 2 is a sectional view on the line 2—2 of Fig. 1. Fig. 3 is a view in side elevation of the controlling annuli. Fig. 4 is a bottom plan view of such annuli. Fig. 5 is a fragmentary top plan view showing a modified construction of shade.

In the present instance, I have shown and described my improved lamp shade as applied to an electric lamp and in this connection I wish it to be understood that the invention, in its useful application, is not limited to this particular purpose, as the same is equally applicable to lamps of other types.

Referring now to the drawing in detail, 1 designates an electric lamp bulb having the butt end thereof threaded into the usual re-

ceptacle 2, such receptacle being formed with a circular bead 3 adjacent to the open end thereof. Encircling the receptacle 2 is an annulus 4 having the inner surface thereof formed with a circular groove 5 designed to receive the bead 3 so that accidental sliding movement of the annulus relatively to the receptacle will be prevented. This annulus 4 is formed of any suitable or desired material and formed in the outer edge thereof, that is, the edge adjoining the open end of the receptacle 2, is a circular series of recesses 5' spaced apart equidistant. 6 designates supporting arms, each having one end coiled upon itself to form a spring 7 and then extended at right angles as at 8 and the remaining end curved as at 9 in a direction opposite to the projecting end 8. The projecting ends 8 of the respective arms 6 are disposed within the recesses 5' in the outer edge of the annulus 4 and appropriately fastened within such recesses, while the springs 7 are spaced apart from the adjacent ends of the annulus and act to hold the arms 6 normally extended outwardly from the lamp 1, such arms radiating from the lamp. Secured to the arms 6 and supported thereby and disposed concentrically of the lamp is a shade 10 formed of any suitable material such, for instance, as paper formed with radial crease lines 11. In the present instance, this paper or cover is plaited as clearly illustrated in Fig. 1 of the drawing. It is conceivable, however, that the paper may be otherwise creased.

Surrounding the annulus 4 is a second annulus 12 having one edge thereof bearing against the inner end portions of the arms 6 and capable of axial movement upon the annulus 4 so that the arms 6 may be swung inwardly toward the lamp 1 when it is desired to contract the shade so as to reduce the area illuminated by the lamp and concentrate the light rays, and outwardly from the lamp when it is desired to increase the area illuminated by the lamp. Formed in the annulus 12 is a cross slot 13 having one side wall thereof formed with rack teeth 14 and engaging the rack teeth 14 is a pinion 15 fixed upon a pin 16 having one end rotatably mounted within a recess in the outer surface of the annulus 4 and the remaining end provided with a knurled manipulating head 17.

In practice, when it is desired to swing the arms 6 inwardly to reduce the diameter

of the canopy or shade, and so diminish the area illuminated by the lamp and concentrate the light rays, the pin 16 is rotated in one direction under the action of the head 17, thereby revolving the pinion 15 and sliding the annulus 12 axially along the annulus 4 so that the outer edge of the annulus 12 will engage the adjacent portion of the arm 6 and swing the latter inwardly against the action of the respective springs 7. On the other hand, when it is desired to increase the diameter of the shade so that the area illuminated by the lamp may be likewise affected, the direction of movement of the pin 15 is reversed, thereby sliding the annulus 12 in the reverse direction to release the arms 6 and permit the springs 7 to react and swing the arms outwardly from the lamp. In the inward movement of the arms 20 under the action of the annulus 12, the shade 10 folds up owing to the radial crease lines therein, while in the outward movement of the arms under the action of the springs 7 the shade unfolds and is stretched.

If desired, the shade 10 may be formed of a series of plates 18, as illustrated in Fig. 5 of the drawing, such plates being secured to and carried by the respective arms 6 and curved longitudinally to conform to the configuration thereof and each having the longitudinal edges thereof overlapping and underlying the respective edges of the adjoining plate.

While I have herein shown and described certain preferred forms of my invention by way of illustration, I wish it to be under-

stood that I do not limit or confine myself to the precise details of construction herein described and delineated, as modification and variation may be made within the scope of 40 the claim without departing from the spirit of the invention.

I claim:

A lamp shade comprising a supporting annulus having a series of recesses formed 45 in the outer edge thereof spaced apart equidistant, supporting arms each having one end coiled upon itself to form a spring and then extended at right angles and disposed within one of said recesses and normally extending radially from said annulus under the action of said spring, said arms being capable of inward swinging movement against the action of the springs to diminish the area illuminated by the lamp, a shade 55 carried by said arms, a second annulus surrounding said first annulus and capable of axial movement thereon to engage the adjacent portions of said arms to swing the latter inwardly and formed with a cross slot 60 having rack teeth on one wall thereof, a pin rotatably mounted within said first annulus and extending through said slot, and a pinion on said pin meshing with said rack teeth whereby the last-mentioned annulus may be 65 moved upon the first annulus.

In testimony whereof I affix my signature in presence of two witnesses.

ISAAC C. TERRY.
